UNITED STATES PATENT OFFICE

DIXON E. WASHINGTON, OF KANSAS CITY, MISSOURI

AUTOMATIC STOP

Application filed November 30, 1927. Serial No. 236,871.

This invention relates to automatic stop and has for its primary object the provision of a device adapted to be affixed to a rotating shaft in such a manner that the reversal from 5 the normal direction of travel of said shaft will cause the stop to operate and preclude any damage which might have resulted from such reversal had this stop not been in place.

The primary object of this invention is 10 to provide a stop which is positive in its action, will operate immediately upon the reversal of the shaft and which has means for permitting a gradual reversal after the operative parts have been moved to the shaft 15 stopping position.

A still further object of the present invention is the provision of an automatic stop which is used in combination with a rotating shaft which stop is provided with a ratchet 20 and cam positioned in juxtaposition whereby the slight movement of the cam will cause stop-dogs to fall into operative relation with the ratchet. Other objects of this invention will appear during the course of the detailed 25 specification referring to the accompanying drawings wherein

Figure 1 is a side elevation of the automatic stop and made in accordance with this invention showing the same anchored in place 30 upon a shaft adapted to be rotated.

Fig. 2 is a top-plan-view of the same as it is shown in Fig. 1.

Fig. 3 is a vertical section of the stop.

Fig. 4 is a vertical cross section of the same 35 taken on line IV—IV of Fig. 3.

Fig. 5 is an enlarged detailed section, showing the operative and inoperative relation of dog and ratchet, and

Fig. 6 is another enlarged detailed section 40 taken on line VI—VI of Fig. 3.

Similar reference characters refer to like parts throughout the several views and the numeral 7 designates a shaft capable of rotation, and upon which this device is to be used.

Shaft 7 normally rotates in the direction of the arrow shown in Fig. 3 and since this stop is used in connection with a device where 50 a reversal of the shaft will cause serious damage, it is desired to have a stop which will

operate as quickly after the reversal of movement as is possible.

Accordingly this invention contemplates a series of elements forming one embodiment of the invention which may consist of a 55 ratchet wheel 8 having the customary teeth 9 inclined in the proper direction to allow unobstructed rotation of shaft 7 in its normal direction.

As is clearly shown in Fig. 4, ratchet 8 is 60 rigidly secured to shaft 7 through the intermediacy of a key or the like 10, thus it is obvious that ratchet 8 will always travel with shaft 7 and through this ratchet shaft 7 will be stopped when the direction of rotation is 65 reversed to the direction opposite from normal.

To fulfill this requirement of the invention, a housing 12 is provided within which is 70 pivotally mounted upon shaft 13 a dog 14 adapted to engage the teeth 9 of the ratchet 8 when the device moves to the operative position. As shaft 7 is moving in the normal direction, dogs 14 are maintained out of engagement with ratchet 8 by a cam 15 which 75 is provided with the proper faces 16 to engage an overhanging portion 17 of the dog 14.

As is plain to be seen in Fig. 4 cam 15 is maintained in engagement with the side of ratchet 8 by a plurality of spring actuated 80 pins 18 and the movement imparted to cam 15 by ratchet 8 may be limited through the use of pins 19, carried by housing 12 and projecting through their respective openings 20 formed through the wall of cam 15. 85

Referring to Fig. 3 and to the description just above set forth, it will be obvious that as the shaft 7 rotates in the direction of the arrow, ratchet 8 will urge cam 15 in the same direction so that openings 20 will lie in the 90 relative position with pins 19 as illustrated. Dogs 14 will be held up by cam faces 16 as shown and immediately upon the reversal of shaft 7, cam 15 will travel with shaft and ratchet 7 and 8 respectively until pins 19 lie 95 against the side of openings 20 at a point directly diametrically opposite to that shown in Fig. 3. When this position is reached, dogs 14 will be released to the action of gravity and will fall in behind the adjacent tooth 100

9 of the ratchet 8. Obviously this connection between shaft and ratchet and the housing 12 will be sudden and solid. Shaft 7 will be arrested by the direct ability of the dogs 14. The load stopped is oftentimes heavy and before readjustment may be affected, shaft 7 must be reversed. When the dogs are locked tight the whole mechanism within and including housing 12 must be allowed to slowly reverse.

One form of embodiment of this phase of the invention is shown here to be an ordinary brake band 20' which may be formed in segments and held against the outer periphery of housing 12 through the use of segmental clamps 21. These clamps 21 are in turn engaged by anchoring bars 22 and the necessary amount of give or slide, in a reversed direction may be provided for 20 through the use of members 23 joining the clamps 21. Obviously the slight amount of adjustment which is needed to set the dogs 14 out of the operative position may be had through the movement of the housing 12 within this anchoring and clamping mechanism.

The operation of this device has been made clear through the specification and while one important embodiment of the invention has 30 been illustrated and described, it is desired to be limited in the construction and use of this invention only by the accompanying claims.

What I claim as new and desire to secure 35 by Letters Patent is:

1. In combination with a rotatable shaft, a stop therefor comprising a ratchet, a housing for the ratchet, a plurality of dogs, a cam adjacent said ratchet having faces to hold said dogs out of engagement with the ratchet and means holding said stop in the operative position adapted to permit gradual reversal of the housing and shaft when the dogs move to the ratchet engaging position.

2. In combination with a rotatable shaft, a stop therefor comprising a ratchet, a housing for the ratchet, a dog, a cam adjacent said ratchet having a face for holding said dog out of engagement with said ratchet, means to yieldably maintain said cam in frictional engagement with said ratchet, a slot in said cam, and a pin on said housing for engaging said slot to provide a lost motion connection between said cam and housing.

3. In combination with a rotatable shaft, a stop therefor comprising a ratchet, a housing for the ratchet, a dog, a cam adjacent said ratchet having a face for holding said dog out of engagement with said ratchet, means to yieldably maintain said cam in frictional engagement with said ratchet, a braking device engaging the periphery of said housing for holding said stop in the operative position and for permitting grad-

ual reversal of the housing and shaft when the dog moves to the ratchet engaging position.

In testimony whereof I hereunto affix my signature.
